UNITED STATES PATENT OFFICE.

ARTHUR C. McGRATH, OF SIOUX CITY, IOWA.

LINOTYPE-MACHINE.

Specification of Letters Patent. Patented Aug. 26, 1919.

1,314,006.

Application filed July 21, 1917. Serial No. 182,033.

To all whom it may concern:

Be it known that I, ARTHUR C. McGRATH, a citizen of the United States, residing at Sioux City, in the county of Woodbury and State of Iowa, have invented new and useful Improvements in Linotype-Machines, of which the following is a full, clear, concise, and exact description, reference being had to the accompanying drawing, forming a part of this specification.

My invention relates to improvements in linotype machines and has for one of its particular objects the provision of means whereby stereotypes may be cast directly from a linotype machine, the present application being a continuation of my application filed October 14, 1916, Serial No. 125,610, as to so much of the subject-matter as was disclosed in said application.

Heretofore it has been customary in setting up advertisements and the like, where stereotypes are used for insertion in the advertisement, particularly for the purpose of illustration, etc., to make these stereotypes by a separate apparatus. This requires considerable time and additional labor in a printing office, and it is one of the objects of my present invention to provide means whereby such stereotypes may be cast directly from the linotype machine by a simple mechanism which may be used on the linotype machine without in any way disconnecting the parts thereof or without disarranging the working parts of the linotype machine.

For the purpose of disclosing my invention, I have illustrated in the accompanying drawings certain embodiments thereof. In said drawings—

Figure 1 is a vertical section through the mold disk and adjacent parts of a linotype machine, showing the mold in position to coöperate with my stereotype mold;

Fig. 2 is a perspective view of the stereotype mold box adapted to be used in connection with the linotype machine;

Fig. 3 is a vertical sectional view of the box shown in Fig. 2;

Fig. 4 is a perspective view of one of the interchangeable liners in the box;

Fig. 5 is a perspective view of a slightly modified form of the casting box, showing the same open; and

Fig. 6 is a fragmentary view in section of the structure illustrated in Fig. 5, with the parts closed.

In the embodiment of the invention illustrated, the linotype machine illustrated is of the usual construction, and I have only shown so much of the machine as is necessary to understand the application of my invention.

In the drawings, the machine is provided, as usual, with the slotted mold 2, in which the linotype slugs, as a rule, are cast. This mold is carried by the rotatable mold-carrying disk 3, which, when the casting operation takes place, brings the mold 2 into position opposite the nozzle 4 of the metal pot 5. The matrix support 6 of the machine is of the usual construction, being provided with a transversely extending slot 7 in which the matrices are adapted to fit, and this slot, as is shown, is provided on one interior face with a rib 8 and on the other 75 interior face with a rib 9. The purpose of these ribs will appear more fully herein-after, as will also appear the purpose of the jib 10 on the bottom of the mold 2. The matrix-holder 6 is mounted on the transversely extending arm 11 of the elevator, the vertically extending arm 12 of which is slidably mounted on the frame 1 and is raised and lowered by the lever 13 pivoted at 14 and being raised into raised position 75 by means of a cam 16 operating upon a roller 17 mounted upon the lever 13.

Fitting in the matrix-holder 6 is a stereotype casting box 18, which preferably takes the form illustrated in Figs. 2 to 4. The casting box illustrated in these figures comprises a pair of plates 19 and 20, one of which at its bottom is provided with an angle flange or bar 21 to which the other plate 19 is hinged, as at 22. These plates 95 are formed of metal and are of such dimensions that in cross-section they approximate the outlines of the standard linotype matrix. The plate 20 is provided at its top with a pair of oppositely disposed ribs 23 100 and 24, and intermediate of its top and bottom, at a point nearer the top than the bottom, the plates 19 and 20 are provided with ribs 25 and 26 respectively. These ribs act as guides in supporting the box in position, as will be apparent from examination of Fig. 1. The ribs 23 and 24, when the box is slid into the matrix-holder, rest on the top shoulders formed by the ribs 9 and 8, while the ribs 25 and 26 engage respectively on the bottom shoulder formed by the rib 8 in the matrix-holder and the shoulder 10 formed on

the mold box 2, so that the casting box is held in position in the matrix-holder in precisely the same manner as the matrix of the linotype machine.

- 5 Under the top or head of the box an undercut groove or recess 27 is formed, which extends across from end to end of the box, so that the stereotype mat 28 may be inserted therein when it is placed in position in the box. The end of this mat 28 is pushed up into the groove so that the molten metal cannot run around and flow back of the mat 28, and the mat thus seals the upper end of the box against the escape of molten metal. The two open sides of the box are closed by liners 29, as is also the bottom of the box. The liners are of the construction shown in Fig. 4 and are formed with grooved edges 30, 30, so that they may be used interchangeably, the grooves providing, as shown in Fig. 4, recesses or undercuts in which the edges of the mat are placed.
- The upper edge of the cover or plate 19 is provided with an inlet opening for the molten metal and this opening is formed by cutting out or grooving the end of the cover, as at 31, so that the cover or plate 19, in conjunction with the head of the box, forms an inlet for the molten metal.
- 30 The plate 20 of the box is preferably formed with air escape openings 32 to permit the escape of the air as the metal is flowed into the box, thereby preventing the formation of air pockets behind the mat 28 and permitting the mat to lie flat against the inside face of the plate 20.

In operation, the casting box is placed in position when the elevator 11, and with it the matrix-holder, is in a raised position. 40 This box is slid in position in substantially the same manner as a matrix is slid in position on the elevator. The elevator then is allowed to drop down until the opening 31 aligns with the mold 2 in the mold-carrying disk 3. Normally this mold 2 provides a mold for the matrix, but when the mold box 18 is placed in position this mold 2 becomes really a nozzle or passage for the molten metal, which is forced out of the metal pot 5 by the usual pumping action used in linotype machines through the mold 2 and into the opening 31 of the mold box. Due to the fact that the metal is pumped or forced into the box, it quickly flows to all parts of the box and is forced against the face of the mat before it has had the slightest opportunity to congeal, so that a much sharper and clearer stereotype is produced in this manner than has heretofore been possible by 55 the ordinary methods of stereotype making.

In Fig. 5 I have illustrated a modified form of the box wherein the head, instead of being formed in one piece, as illustrated in the structure shown in Fig. 2, has a sec-

tion thereof formed on each one of the plates, the meeting faces of the plates being beveled, as at 33, and the inlet for the metal being in the form of a slot 34 through the plate 19.

In using the box as above described in connection with the linotype machine, before inserting the box in position the box cover is swung open, as illustrated in Fig. 5, and the mat is laid against the inner face of the plate 20, the upper edge being inserted in the groove 27. Two of the liners 29, 29 are then placed in position at the ends of the box and a bottom liner is placed in its position at the bottom of the box, all of the liners having their grooved edges extending over the ends or edges of the mat. The box cover is now closed and after being warmed sufficiently to prevent chilling the molten metal too quickly, the box is placed in the elevator, as above described and the stereotype cast.

In order that the box may always be ready for use, and so that the operator will not have to stop and warm the box whenever it is desired to use the same, I preferably provide on the side of the metal pot 5— which is kept hot, of course, in order to keep the metal in a molten state—a pocket of any suitable construction 35, in which the box may be kept when not in use, so that it will be kept at substantially the same temperature as the metal pot.

Having thus described my invention, what I claim as new and desire to secure by Letters Patent, is:—

1. The combination with a linotype metal pot, of a linotype elevator, a matrix-holder for said elevator, and a molten metal container independent of the linotype mold for receiving a stereotype mat supported by said elevator and arranged to be moved into a position to receive the molten metal from said metal pot.

2. In combination, a molten metal container independent of the linotype mold arranged to receive a stereotype mat and having in cross-section the approximate outline of a standard linotype matrix and a linotype elevator supporting said container and moving said container into position to receive the molten metal from said metal pot for casting a stereotype.

3. The combination with a linotype machine, of a casting box therefor having open ends and comprising a pair of hinged, spaced plates, one of said plates formed with a bottom flange and an upper lug and forming bottom and top closures for the box, the upper closure formed with a recess to receive the edge of a matrix, and interchangeable, removable liners adapted to retain the edges of the matrix and close the open ends of the box.

4. The combination with a linotype machine, of a casting box therefor comprising a body plate having an integral bottom angle bar, a cover plate hinged to the bar and forming an open end casting box, said 5 body plate having a portion overlapping the other plate to form a closed upper end to the box, and removable liners adapted to retain a matrix and close the ends of the box.
5. The combination with a linotype machine, of a casting box therefor comprising a pair of spaced, hinged plates forming respectively the casting box body and cover, there being an overlapping joint at the free 10 ends of the plates forming a closed upper end to the box, and the upper edge of the cover having a recess therein forming, in conjunction with the box body, an inlet opening for molten metal.
6. The combination with a linotype machine of a casting box therefor comprising a pair of spaced, hinged plates forming respectively the casting box body and cover with an overlapping joint closing the upper 15 end of the box, a matrix-receiving groove formed in the upper end of the box, and matrix-retaining liners closing the open ends 20 of the box.
7. The combination with a linotype machine of a casting box therefor comprising a pair of hinged, spaced plates forming an open end casting box having a closed bottom, one of said plates having a portion 25 overlapping the other plate forming a closed upper end to the box and provided with a recess to receive the upper edge of the ma-
- trix, and removable liners adapted to retain the matrix and close the ends of the box.
8. In combination with a linotype machine having a metal discharge nozzle, a rotatable 40 mold-carrying disk rotatable to bring the molds thereof opposite said nozzle, a matrix elevator and a molten metal container constructed to receive a stereotype mat and having a portion thereof in cross-section of a 45 configuration to fit the matrix-receiving portion of said elevator, carried and moved by said elevator into position to receive molten metal from said pot through said mold, said container having a metal-receiving opening 50 coinciding with the mold of the linotype machine when the elevator moves the container and mold to operative position.
9. The combination with a linotype machine, of a molten metal container independent of the linotype mold constructed to receive a stereotype mat and having a portion thereof in cross-section the approximate outline of a standard linotype matrix, and a metal-receiving opening in the face thereof 60 constructed to coincide with the opening of the linotype mold.
10. In a linotype machine, the combination with a metal pot, of an elevator and a molten metal container independent of the 65 linotype mold for receiving a stereotype mat supported on the elevator frame in a position to receive the molten metal from said metal pot.
- In witness whereof, I have hereunto subscribed my name.
- ARTHUR C. McGRATH.
